CABINET FOR ELECTRONIC EQUIPMENT

William F. Dalton, Hopewell Junction, and Arnold M. Davis, Walter F. Kraus, and Walter S. McCormick, Jr., Poughkeepsie, N.Y., assignors to International Business Machines Corporation, New York, N.Y., a corporation of New York

Filed Feb. 26, 1964, Ser. No. 78,786

Term of patent 14 years

(Cl. D26—5)

FIG. 4

FIG. 2

FIG. 3

FIG. 1 is a perspective view showing the cabinet incorporating our new design as seen from the left front side.

FIG. 2 is a perspective view of the rear and left side of FIG. 1.

FIG. 3 is a perspective view of the rear and right side of the invention.

The forwardly facing sides of the sections extending to the left in FIG. 2 and the side in FIG. 3 containing the glass are similar. In FIG. 3, the forwardly facing sides of the sections extending to the right are similar.

We claim:

The ornamental design of a cabinet for electronic equipment, substantially as shown and described.
